MACHINE FOR MAKING LINK RODS

Eben D. Dahlman, Grandy, Minn.

Application November 15, 1937, Serial No. 174,588

20 Claims. (Cl. 153—4)

This invention relates to a machine for making certain link rods, one use of which rods is for forming a sorting chain or device in a potato picking or grading machine. Such rods 5 have a rectilinear central or intermediate portion and have their ends bent inwardly and then bent at right angles to form open loops.

It is an object of this invention to provide a simple, efficient and automatic machine which 10 will produce said rods very rapidly.

It is a further object of the invention to provide a machine which will produce said rods from the original stock and which will deliver said rods to an intermittently movable conveyor 15 on which they are automatically arranged in interengaged relation.

It is still another object of the invention to provide a machine comprising a plurality of dies 20 for bending the ends of the rods together with means for taking the rods from a point of delivery such as a furnace, delivering the same to said dies and delivering them to a guide-way by which they are guided to the receiving means, such as the conveyor above mentioned.

It is still further an object of the invention 25 to provide a machine comprising bending dies, means for delivering the rods to said dies, means for removing the rods from said dies, and intermittently movable conveyor to which the rods 30 are delivered together with means for operating all of said parts in synchronism.

These and other objects and advantages of the invention will be fully set forth in the following description made in connection with the 35 accompanying drawings in which like reference characters refer to similar parts throughout the several views and in which:

Fig. 1 is a view in side elevation of the machine also showing a furnace, a part of which 40 is shown in vertical section and in which view some of the parts are broken away;

Fig. 2 is a top plan view of the machine also showing a portion of a furnace;

Fig. 3 is a view in side elevation of the machine as seen from the side opposite that seen 45 in Fig. 1;

Fig. 4 is a vertical section taken substantially on line 4—4 of Fig. 2 as indicated by the arrows;

Fig. 5 is a partial plan view of the bending dies in open position;

Fig. 6 is a view similar to Fig. 5 showing the dies with the rod partially bent;

Fig. 7 is a view similar to Fig. 5 showing the 55 dies in the final position of bending;

Fig. 8 is a perspective view of the finished rod; and

Fig. 9 is a partial plan view of the delivery end of the machine.

Referring to the drawings a machine is shown 5 comprising a frame designated generally as 10, which frame has spaced vertical side or leg portions 10a connected by top horizontal portions 10b and intermediate horizontal portions 10c. A top plate 10e extends between the side portions and end rails 10f extend from the feeding end of the machine toward a furnace 11, part of which is shown and which has supporting legs 11a. The furnace 11 will comprise means for heating the straight rods 12 and these will 10 be progressively discharged in a row resting on the bottom of a passage 11b forming an exit from said furnace. A pair of brackets 13 are provided having flanges 13a secured to the discharge side of the furnace by cap screws 14a. 20 These brackets are also secured to the rails 10f and as shown in Fig. 1, extend downwardly from passage 11b to said rails.

A pair of stop pawls 14 are pivoted on pivots 15 at the inner side of brackets 13 and are 25 held in position shown in Fig. 1 by small compression springs 16 disposed at the underside thereof and bearing at their other ends on lugs 13b depending from brackets 13. Springs 16 are shown as having their ends secured by riveting to arms 14 and lugs 13b. Brackets 13 also have upstanding lugs 13c at their upper ends to which are pivoted by the pivot screws 17 pawls 18 held in the position shown in Fig. 1 by tensile coiled springs 19 secured to the lower end 30 of pawls 18 and at their other ends to small angle brackets 20 secured to the tops of arms 13. Bearings 21 are secured by suitable bolts 22 to the outer ends of the side rails 10f and form bearings for a rod 23 extending therebetween. Rod 23 has secured thereto adjacent each bearing 21 an arm 24. Arms 24 are of a 35 length to extend substantially to the furnace 11 and terminate in slightly curved pointed ends 24a. A gripping member 25 is pivoted to the outer side of each arm 24 by the screw 26. Gripping member 25 has a gripping jaw or plate 25a arranged in opposite relation to the concave side of end 24a. Member 25 has a pocket at its inner end of general semi-cylindrical shape 50 in which is disposed the ball end on the short arm of a lever 27 pivoted to the inner side of arm 24 by a pivot screw 28. The long arm of lever 27 extends toward the pivoted end of arm 24 and has secured to its end one end of 55

a coiled torsion spring 29, the other end of which is secured to the top of lever 24 by screws 30. The arms 24 swing downwardly against arms 14 which are depressed and thus will allow the 5 outermost rod 12 to roll between jaw 25a and point 24a. Member 25 is rocked somewhat by engagement with arm 14 so that the rod 12 can move completely within jaw 25a. When arm or arms 24 are again raised the rod 12 is gripped 10 between jaw 25a and point 24a and arms 14 again rise to prevent the egressing or dropping of the outermost rod 12.

Rod 23 has secured to its end outside of one of the bearings 21 an arm 31, which arm has 15 pivotally secured to its end one end of a link 32 which in turn is pivotally secured at its other end to an arm 33, secured to and rotatable with a shaft 34 extending transversely of frame 10 and journalled in bearings 35 secured to 20 frame members 10c by screws 36. It will be seen that when shaft 34 and arm 33 are rotated that link 32 will swing arm 31 which will in turn oscillate shaft 23 and swing arms 24. Members 37 secured by one of the bolts 9 which hold rails 25 10f upstand from said rails in position to be engaged by the long arms of levers 27 when the latter are swung to stationary position.

Disposed on plate 10e are spaced stationary dies 38, the same being shown as having substantially semi-cylindrical outer sides. Guiding members 39 shown as formed from flat bars bent into substantially inverted V-shape are disposed adjacent dies 38 so that a rod 12 may be disposed between one side of guide members 39 and the 35 dies 38. Movable or swingable dies 40 are disposed adjacent dies 38 and mounted to swing about vertical pivot bolts 41 which secure them to plate 10e, said bolts having washers 42 beneath the heads thereof. Each die 40 has a bending face or surface 40a and a supplementary die 40b thereon projecting from face 40a and having an outer substantially semi-cylindrical side. Dies 40 are pivotally connected at their inner 40 ends respectively to links 43, which links are pivotally connected at their other ends by pivots 44 45 to a cross-head 45. Cross-head 45 is movable in guides formed below plate 10e and has depending therefrom a lug 45a to which is pivotally connected one end of a link 46, the other end of 50 which is pivotally connected to the upper end of a lever arm 47. Lever arm 47 is pivotally connected at its lower end by pivot stud 48 to a bracket 49 secured by screws 50 to one of the cross frame members 10c. Lever 47 has revolvably 55 mounted thereon a roller 51 engaged in the groove 52a of a cam 52 rigid with and revolvable with shaft 34. Cam 52 will thus swing arm 47 to the dotted line position shown in Fig. 4 and will thus advance cross-head 45 and through links 43 will 60 swing the die members 40. With the rod 12 in the position shown in Fig. 2 the dies 40 bend the same about die 38 to the dotted line position shown in said figure. With the rod bent the projections 40b move into position over the bent portion 65 of the rod.

Dies 55 are provided having arm portions and hubs secured to the opposite ends of a shaft 56 journalled in bearings 57 secured to plate 10e by the bolts 58. Shaft 56 has secured thereto an 70 arm 59 to the end of which is pivotally connected a link 60. Link 60 is pivotally connected at its other end to one end of a cam lever 61, which lever is pivoted at its other end by pivot 62a to one of the frame members 10a. Lever 61 has revolvably 75 mounted thereon a roller 62 engaged by a cam

member 63 secured to shaft 34. An arm extends substantially parallel to lever arm 61 having its ends bent at right angles, one of which ends is pivoted to lever 61 by the bolts 65. The other end of said arm 64 has a roller 66 revolvably mounted thereon which also engages cam 63. An arm 67 has an elongated slot 67a therein through which extend spaced screws 68 holding said arm in place. Arm 68 has a roller 69 revolvably mounted at its outer end and adapted to engage one side of the link 60. A tensile coiled spring 70 has one end secured to link 60 and its other end secured to frame member 10a and acts to hold roller 62 against cam 63. It will be seen that when cam 63 revolves lever arm 61 will be moved upwardly as will link 60 and arm 59 will oscillate shaft 56 so that dies 55 will be moved upwardly. As dies 55 move upwardly the ends of the rod 12 are engaged as shown in Figs. 6 and 7 and the end of the rod is bent around the die or projection 40b thus forming an open loop on the rod with a semi-circular end. The terminal portion of the rod projects tangentially at the upper side of this loop.

A shaft 72 is journalled in bearings 73 secured to the plate 10e by screws 74. A pair of arms 75 have hubs secured to shaft 72 as by the pins 76. Arms 75 swing to a position shown in Figs. 2 and 4 where their ends underlie rod 12 in its position in the dies. Arms 75 have upturned ends 75a. Curved bars 77 are disposed at each side of the machine having ends extending substantially vertically adjacent the dies 38 and at the inner sides thereof. Bars 78 are also provided above bars 77 and spaced some distance therefrom, the forward end of bars 78 having bent parts terminating some distance above the plate 10e. Bars 77 and 78 are carried on side brackets 78a and 80 secured by suitable screws to plate 10e. The curve on bars 77 and 78 is substantially concentric with shaft 72. Shaft 72 projects at one side of the machine and has secured thereto an arm 81 the outer end of which is pivotally connected to a link 82 by a pivot bolt 83. Shaft 72 has a pin 84 projecting upwardly and laterally therefrom as shown in Fig. 1, the same having an eyelet at its upper end to which is secured one end of a tensile coiled spring 85, the other end of which is attached to an eyelet 86 secured in one of the frame members 10a. A coiled spring 87 has one end secured to the lower end of lever 82, which lever extends downwardly, and to the left as shown in Fig. 1, the other end of spring 87 being secured to one of the cross frame members 10c. Lever 82 has a shoulder 82a formed thereon extending at right angles to the lower side of said lever, said lever is disposed close to a cam plate 88 having revolvably mounted thereon a cam roller 89. Cam roller 89 is arranged to engage shoulder 82a and to move lever 82 in the 60 revolution of cam plate 88. A stop lug 90 is secured to the side of cam plate 88 by a screw 91. A rib 88a of curved form upstands from the surface of cam plate 88. Cam plate 88 also has upstanding from the surface thereof a lug 88b 65 shown as of rectangular form through which is threaded a headed screw 92. Screw 92 engages and moves a block 93 having a portion movable in and guided in a slot 88c formed in plate 88. At the other side of said plate from lug 88b 70 block 93 carries a roller 94. Plate 88 is secured to a gear 95 secured to shaft 34 by which said shaft and the parts attached thereto are driven. Gear 95 is in mesh with and rotated by a pinion 96 secured to a shaft 97 journalled in bearings 75

98. Shaft 97 has secured thereto at one side of the machine, a pulley 99 which will be driven by some suitable motor. A clutch preferably will be used with pulley 99 of the stop type adapted to 5 make a certain revolution after being tripped. Such clutches are well known and the same is not illustrated although the tripping mechanism for said clutch is illustrated comprising a pedal lever 101 pivoted on pivot 102 to one of the frame members 10a, the same being shown as having a pedal portion 101a at its outer end. Lever 101 is pivotally connected at its inner end to a link 103 movable in a guide member 104 secured to one of the cross-bars 10c by the bolts 105. A lever 106 is pivoted at 107 to the frame member 10a and extends along the frame to engage at its 10 other end a stop member 108. Lever 106 is also connected by a link 109 to an arm 110 pivoted on stud 111.

20 The rod after being bent in the dies described is swung by operation of arm 75 through the guide-way formed by bars 77 and 78. A bracket 115 is secured to member 78 adjacent its rear end and projects upwardly therefrom to have 25 pivoted thereto by the pivot member 116 an escapement lever 117. The lever 117 has spaced prongs 117a, the ends of which are disposed close to bar 77. A link 118 connects the upper end of lever 117 to one of the dies 40. Spaced guide plates 112 extend parallel to bars 77 and 78, and some distance outwardly therefrom, the same being spaced slightly more than the bent rod 12. A bar 120 extends transversely adjacent one end of frame 10, the same having angular portions secured to the frame members 10a by screws 121. Another bar or plate 122 extends transversely of the machine some distance in the rear of bar 120 and has arm brackets 122a secured to frame member 10a by screws 123. Bars 124 project inwardly from brackets 122a and extend upwardly to overlap bar 120.

25 A conveyor is provided comprising spaced sprockets 126 secured to a shaft 127 journalled in bearings projecting from frame 128. Another pair of sprockets 129 are secured to a shaft 130 also journalled in bearings carried on frame 128, sprockets 129 being alined respectively with sprockets 126. Chains 131 run over the pairs of aligned sprockets 126 and 129 respectively. A 30 ratchet wheel 132 is secured to shaft 130 and is engaged by an actuating pawl 133. Pawl 133 is mounted on a pivot 134 connecting a lever arm 135 with a link 136. Lever arm 135 is pivoted on shaft 130 and extends equal distances above 35 and below said shaft, the same having a link 137 pivotally connected to its lower end by pivot member 138. Links 136 and 137 are pivoted respectively to the ends of lever arms 139a extending equal distances at each side of a pivot member 140 secured in frame 128. Arms 139a are part of a lever 139 which lever has a main arm extending along one side of the cam plate 88 and arranged to be engaged by roller 94. A tensile coiled spring 119 has one end secured to 40 lever 139 and has its other end secured to one of the frame members 10a. Another pawl 141 engages ratchet wheel 132 at the front side thereof and is pivoted to a lever 142, which lever is fulcrumed on a pivot 143 mounted in a lug depending from the top of frame 128. Lever 142 has secured thereto a link rod 144 which will extend to the forward end of the machine in position to be manipulated by the operator for manually operating ratchet 132 if this is desired.

45 In operation, the rods 12 will be cut to the right length and heated in furnace 11. The rods will be discharged through passage 11b so that they pass from the end of said passage downwardly onto bracket 13 until the foremost rod engages the stop member or pawl 14. At this 5 time spring 19 holds the pawl 18 just above the top of pawl 14 at the end thereof. Pulley 99 will be rotated and when the operator steps on clutch pedal 101a the clutch will be engaged and gear 95 will be rotated by pinion 96. This will 10 rotate shaft 34 and crank 33 will, through link 32, oscillate arm 31 and arms 24 will be swung downwardly over members 14. Members 14 will be depressed by engagement therewith of member 25 and one of the rods 12 will pass over the 15 end of members 14 on top of jaw member 25a. Member 25 will be rocked somewhat by engagement with members 14 so that jaw member 25a will move away from end portion 24a to enable said rod to move against member 25. Arms 24 20 will then be swung upwardly permitting members 14 to rise to the position shown in Fig. 1 and spring 29 will close jaw 25a against rod 12 gripping it against end portion 24a. The pointed ends of pawls 14 pass between the discharged 25 rod and the next adjacent one as said pawls move upward. Members 18 act to control the rods and prevent their moving upwardly. When arms 24 are swung upwardly the rods move members 18 against the tension of springs 19 so that 30 the rods snap past said members. Arms 24 are swung in an arc of somewhat less than 180 degrees and come into position where the arms of levers 27 engage members 37. This swings members 25 and moves jaws 25a away from portions 35 24a so that the rods are released. The rods then drop between the front end of the curved bars 77 and guiding members 39 and come into position in the rear of the stationary dies 38 as shown in Figs. 1, 2 and 5. With the rod in this position cam 52 acts on lever arm 47 to move cross head 45 rearwardly and this through the links 43 swings the movable dies 40 to bend the ends of the rod around the stationary dies 38 as illustrated in Fig. 6. The dies or projections 40b 45 on dies 40 come into position over the bent portion of the rod as seen in Fig. 6. The movable dies 40 are held in the position shown in Fig. 6 while cam 52 continues its rotation with the surface thereof concentric with shaft 34 engaging 50 roller 51. Cam 63 now raises lever arm 61 by engagement with rollers 60 and 62 thus raising link 60 and swinging arm 59 upwardly. As lever arm 61 is raised cam roller 69 engages link 60 to swing it rearwardly somewhat and insure 55 that a dead center position is not attained with arm 59. When arm 59 is swung upwardly the dies 55 are swung upwardly and the terminal portions of the rod 12 are bent over the dies 40b, as shown in Fig. 7. A loop is thus formed at the 60 end of each rod and the terminal portion of the rod extends tangentially to one side of this loop. With the continued rotation of shaft 34 the cross head 45 is retracted by cam 52 and lever 61 is again lowered by spring 70 as cam 63 revolves 65 so that its short radius is in engagement with rollers 62 and 66. With the dies are thus again moved away from the rod, roller 89 in the rotation of cam disk 88 with shaft 34 engages shoulder 82a of lever 82 and moves said lever to the 70 left as shown in Fig. 1. This rotates arm 81 in a clockwise direction and arms 75 are oscillated quickly in a clockwise direction. It may be stated that rib 88a is provided to support arm 82 in the rotation of disk 88 after said arm is dis-

75 In operation, the rods 12 will be cut to the

engaged by roller 89. In the rotation of disk 88 roller 89 moves arm 82 against the tension of springs 85 and 87. Roller 89 finally comes into position where it moves off of shoulder 82a and lever arm 82 snaps down against stop 90. Arms 75 are thus very quickly snapped back into receiving position as shown in Fig. 4. Plates 112 prevent the rod from moving endwise while it is being swung between plates 77 and 78 by the arms 75. When arms 75 are swung in a clockwise direction the rod 12 is lifted and moves along bar 77 and between the same and bar 78 as illustrated in Figs. 1, 2 and 3. The rod thus comes into position against the rearmost prong 117a of the escapement lever 117. The rod remains here until the dies 40 are again operated, at which time lever 117 is oscillated by link 118 and the rod is released by the rearmost prong 117a and the foremost prong 117a prevents another rod from being released. The rod released drops down onto bar 120 as illustrated in Fig. 1 and then tips by gravity turning through substantially 90 degrees and then drops vertically. Plate 122 prevents the rods from moving too far rearwardly and the rods are guided in their vertical movement by the bars 124. There is enough of a recess or groove as it were, in the ends of the rod to make it guide nicely along the bars 124. The rod 12 drops onto the conveyor formed by chains 131 and the terminal portions 12a of the rod hook over the bight 12b of the previously discharged rod so that the rods interengage to form a chain and move in this condition with the conveyor. At each revolution of cam plate 88 the roller 94 engages lever arm 139 and lifts the same, said arm being retracted by spring 119. The position of the roller 94 can be adjusted by screw 92 to get the desired movement of lever 139. When lever 139 is thus raised it oscillates about pivot 140 and the upper arm 139a through link 136 rocks lever 135 thus moving pawl 133 to rotate ratchet 132 a distance of one tooth. This moves the chain 131 a sufficient distance so that the rod last delivered will be in position to be engaged by the rod next delivered. The conveyor is thus moved in synchronism with other parts of the machine.

It is thus seen that the operation of the machine is automatic and that all parts move in synchronism. The rod is, as described, picked up and delivered by arms 24, it is then bent by the dies, delivered by arms 75, dropped through the guideway formed by members 122 and 124 and engaged with the previous rod on the conveyor. The operation of the machine is thus quite rapid. As stated, the conveyor may at times be advanced by operation of rod 144 by the operator when desired.

From the above description it is seen that applicant has produced a comparatively simple and very efficient automatic machine for making the link rods. The machine is quite rugged and durable and requires little attention for maintenance. There are no fine adjustments to cause trouble. The machine has been amply demonstrated in actual practice and has been commercially used.

It will, of course, be understood that various changes may be made in the form, details, arrangement and proportions of the parts, without departing from the scope of applicant's invention, which generally stated, consists in a device capable of carrying out the objects above set forth in the parts and combinations of parts disclosed and defined in the appended claims.

What is claimed is:

1. A machine for making link rods such as used in potato pickers having in combination, a stationary die, means for delivering a rod to engage one side thereof with said rod projecting beyond said die, a second die movable to bend said end portion about said stationary die through substantially 90 degrees and having a projection thereon movable over said rod in its bent position, a third die movable upwardly in an arc to bend the terminal portion of said rod over said projection to form a loop disposed in a plane substantially perpendicular to the length of said rod, swinging means for engaging said bent rod and moving it from said dies and means for moving said second and third dies and said last mentioned means in synchronism to bend and move said rod. 15

2. A machine for making link rods such as used in potato pickers having in combination, a stationary die having a substantially semi-cylindrical side, means for delivering a rod adjacent said die with its end portion projecting beyond said die, a second die movable to bend said end portion about said stationary die through substantially 90 degrees to form a bight, a third die movable into position over said rod in its bent position, a fourth die movable vertically in an arc to bend the terminal portion of said rod over said third die to form an open loop disposed in a plane substantially at right angles to the length of said rod, swinging means movable in a plane substantially at right angles to the length of said rod for engaging the same and moving it from said dies and means for moving said second, third and fourth dies and said first and second mentioned means in synchronism for bending and moving said rod. 20

3. A machine for making link rods such as used in potato pickers having in combination, bending dies for bending the ends of a rod inwardly and then into a semi-cylindrical loop in a plane at right angles to said first bend with the free end of said rod projecting at one side of said loop, means for engaging said rod and swinging the same through an arc of substantially 180 degrees at right angles to its length and releasing said rod, a member against which said rod is delivered and about which it fulcrums by gravity to turn to a position with the open side of said loop directed downwardly, guiding means for guiding said rod as it drops from said member, a conveyor for successively receiving said rods disposed below said guiding means and onto which said rods drop from said guiding means in engaging relation to form a chain and means for operating said dies and said first mentioned means and intermittently moving said conveyor in synchronism. 45

4. A machine for making chain rods such as used in potato pickers having in combination, bending dies for bending the ends of a rod inwardly and then bending the terminal portions substantially at right angles to said first bend to form loops with the ends of said rod projecting from said loop, means for delivering a rod to said dies, and means swingable in an arc in a plane perpendicular to the length of said rod for removing said bent rod from said dies and a curved guide bar along which said rod is moved by said last mentioned means. 60

5. A machine for making chain rods such as used in potato pickers having in combination, stationary dies, a pair of swinging arms having gripping means engaging said rods for swinging said rods and depositing the same adjacent said 75

5 dies, movable dies for bending the ends of said rods inwardly and then upwardly respectively to form open loops at its ends, arcuate guiding means adjacent said dies, a pair of swinging arms for lifting said rod and moving the same from said dies along said guiding means and discharging said rod.

6. A machine for making chain rods such as used in potato pickers having in combination, a 10 pair of spaced stationary dies, means for disposing a rod adjacent the same with its ends projecting beyond said dies respectively, a second pair of dies swingable in horizontal planes to bend the ends of said rod inwardly through substantially 15 90 degrees, a third pair of dies movable with said second pair into alignment with said rod in bent position, a fourth pair of dies movable in substantially vertical arcs for bending the ends of said rod into an open loop and in a 20 plane substantially at right angles to the length of said rod, means for engaging said bent rod and swinging it away from said dies and means for moving said second, third and fourth pair of dies and both of said means in synchronism for 25 bending and moving said rod.

7. A machine for making chain rods such as used in potato pickers having in combination, bending dies, an inclined support down which said rods move, spaced stops for said rods, movable means engaging a rod in contact into said stops at spaced points and swinging the same to position in said dies, means for swinging the same away from said dies after being bent, means for receiving and conveying said rod, 30 means for receiving said rod from said second mentioned means and directing it to said last mentioned means, and means for actuating said dies and all of said means in synchronism.

8. A machine for making chain rods such as 40 used in potato pickers having in combination, bending dies, an inclined support down which said rods move, movable means engaging the endmost rod, spaced swinging arms, pivoted levers carried on said arms respectively adjacent the ends thereof having end portions having gripping jaws, resilient means holding said jaws in gripping position, means for swinging said arms to cause engagement of said levers and first mentioned means to move said first mentioned 45 means to release said endmost rod and allow it to move into said jaws, and means for swinging said arms to convey said rod in said jaws to said bending dies.

9. The structure set forth in claim 8 and means 50 adjacent said dies engaged by said levers as they approach said dies to open said jaws and deliver said rod.

10. A machine for making link rods such as used in potato pickers, having in combination, 55 bending dies for receiving and bending the ends of a rod, a pair of arms movable to a position beneath said rod within said dies, a guiding means formed of spaced arcuate bars and means for rapidly swinging said arms about an axis concentric with said bars to move said rod along said bars.

11. The structure set forth in claim 10, a guide plate along the sides of and substantially 60 parallel to said bars.

12. The structure set forth in claim 10 and another pair of bars spaced above and substantially parallel to said first mentioned bars respectively.

75 13. The structure set forth in claim 10, said

bars having a downwardly inclined delivery end, escapement means at the ends of said bars holding the endmost rod thereon and means for swinging said escapement means to release said endmost rod and retain the next adjacent rod.

5

14. A machine for making link rods such as used in potato pickers, having in combination, bending dies, a guiding means formed of arcuate bars extending from adjacent said dies, means for swinging a rod bent by said dies along said 10 bars, said bars having inclined delivery ends, an escapement lever having spaced prongs carried on one of said bars, one of said prongs engaging the endmost rod to hold it on said bars, and means for swinging said escapement lever to 15 cause said prong to release the endmost bar and said other prong to hold the next bar in position.

15. A machine for making link rods such as used in potato pickers having in combination, a 20 bending die, means for engaging a rod at spaced points and swinging the same from a place of discharge, such as a furnace, in a path perpendicular to its length to dispose it in operative position to said bending die, a second and movable 25 bending die cooperating with said die for bending the ends of said rod inwardly to form a bight, a third bending die for bending the ends of said rod upwardly to form an open loop disposed in a plane at right angles to the plane of said bight, 30 means swingable through substantially 180 degrees for engaging said rod and transferring it from said dies through a path in a plane perpendicular to its length and an escapement means against which said rods are delivered.

35

16. The structure set forth in claim 15, a downwardly inclined support for said rod while held by said escapement, means for operating said escapement to permit said rod to move from said support by gravity, a member against which said 40 rod is delivered disposed so that said rod falls by gravity therefrom with the open ends of said loops directed downwardly, a member upon which said rods are received movable to hold the previously delivered rod in vertical alinement with 45 the rod being dropped whereby said loops may engage over said previously delivered rod on said last mentioned member.

17. The structure set forth in claim 15, means for operating said escapement to release said rod, 50 a bar against which said rod is dropped and on which it fulcrums to move to position with the open ends of said loops directed downwardly, a guide means for guiding said rod vertically in said position, a conveyer for receiving said rod 55 below said guide means intermittently movable to hold the last rod received in position to be engaged by said open loops on said rod as it moves from said guide means whereby said rods 60 become disposed in interengaged relation.

18. A machine for making chain rods such as used in potato pickers having in combination, bending means for bending the ends of a rod inwardly to form a bight and then bending said 65 ends to form open loops disposed in planes at right angles to the planes of said bights respectively, means for removing said rod so bent from said bending means, a vertically extending guide means, means for delivering said rod to said guide 70 means with the open ends of said loops directed downwardly, a conveyer constructed and arranged to receive said rods from said guiding means intermittently movable to hold the last rod received in alinement with said guiding 75

means, whereby a rod drops from said guiding means onto said conveyer and said loops engage with the last rod received on said conveyer.

19. A machine for making link rods such as used in potato pickers having in combination, bending dies for bending the ends of said rod inwardly and upwardly to form open loops at said ends, means for feeding said rods to said dies, means for engaging said rod at spaced points and swinging the same away from said dies through a path perpendicular to its length, a member onto which said rod is delivered in position to swing by gravity into a position with the open ends of the loops directed downwardly, vertical guide means for guiding said rod in said position for downward movement, a conveyer for receiving said rods below said guide means onto which said rods drop in interengaged relation from said guide means and means for operating

said dies and first two mentioned means in synchronism.

20. A machine for making link rods having in combination, bending dies for bending the ends of said rod to form open loops at said ends, means for engaging said rod at spaced points and swinging the same away from said dies, a delivery means, a member against which said rod is delivered by said last mentioned means in position substantially similar to that which it occupied in said dies and from which position it swings by gravity through substantially 90 degrees to bring the open ends of said loops directed downwardly, a guide means for guiding said rods downwardly in said latter position, a conveyer for receiving said rods below said guide means onto which said rods drop in interengaged relation and means for operating said dies and first two mentioned means in synchronism.
